UNITED STATES PATENT OFFICE.

HENRY B. NICHOLS, OF PHILADELPHIA, PENNSYLVANIA.

SIDE AND CENTER BEARING FOR VEHICLES.

1,116,103.

Specification of Letters Patent.

Patented Nov. 3, 1914.

Application filed September 23, 1911. Serial No. 650,988.

To all whom it may concern:

Be it known that I, HENRY B. NICHOLS, a citizen of the United States, residing at Philadelphia, in the county of Philadelphia and State of Pennsylvania, have invented a certain new and useful Improvement in Side and Center Bearings for Vehicles, of which the following is a specification, reference being had therein to the accompanying drawing.

My invention relates to railway cars and especially to the means for connecting the trucks to the bodies of such cars.

It has for its object the provision of such means which will permit lateral motion and angular displacement in all directions of the car trucks without twisting or racking the car bodies or binding the trucks. Heretofore, with the ordinary construction, there have been center bearings and side bearings provided for car trucks, but their rotary motion, permitting angular displacement, has been confined to a horizontal plane so far as I know. Hence, any angular displacement in a vertical plane of one truck without a corresponding displacement of the other, must result in the straining and twisting of the car body. This is very noticeable in the case of long and heavy cars with double trucks such as are now employed, for example in subway service, where the curves are frequently of short radius, and of necessity heavily banked up, and high speeds are maintained in order to satisfy rapid transit schedules. In such case the forward truck of a long car might reach the steepest portion of the curve before the rear truck had started to spring from the straight line. The strain on the car body is obvious, and in addition to the wear on the rolling stock, there is added strain on the rails, and some discomfort to the passengers.

I attain my object by providing center and side bearings for each truck, arranged in the surface of a sphere whose radius is determined with respect to the rise and radius of the curves, so that angular displacement is possible in all directions, in planes which cut the spherical surface in great circles, on which roll antifriction devices such as hardened steel balls. In use I find that cars equipped with these center and side bearings may be run at any speed around curves of any radius which will take their dimensions, without discomfort to the

passengers, smoothly, and without strain or damage to the cars.

My invention is illustrated as to one embodiment in the accompanying drawings in which—

Figure 1 is an end view diagram of a car, with its trucks angularly displaced in opposite directions. Fig. 1^a is a similar diagram taken at right angles to Fig. 1, showing the spherical surface in which the bearings are arranged so as to permit universal rotary motion of the truck around a center lying above the same in the body of the car. Fig. 2 is a diagram showing a curve with a car thereon in plan. Fig. 3 is a plan view of one form of my spherical center and side bearings. Fig 4 is a plan view of the truck bearings with the body detached therefrom. Fig. 5 is a side view of the parts shown in Fig. 3. Fig. 6 is an enlarged detail view of the center bearing, along the section line x—x of Figs. 4 and 5. Figs 7, 8 and 9 are similar detail views of the side bearings, parts in Fig. 9 being shown in section.

Referring to the drawings and especially to Figs. 1, 2, 3 and 5, C is a car body provided with trucks C', C², fitted with the usual wheels W, and each truck turning under the body on a kingbolt 7. In Fig. 2 a track curve is shown at T, the car moving in either direction, and the truck C² located on a heavy rise of the curve while the truck C' has not yet sprung from the straight line and consequently is still level. The body of the car is indicated in dotted lines in this figure, which is intended merely as illustrative of the conditions which my invention is intended to meet. In Fig. 1 which is the end view, one truck (in full lines) is shown displaced to the left, and the other truck (in dotted lines) displaced to the right. While this particular condition would rarely exist, and while the degree of separation of the wheels W' and W² from normal position is exaggerated, this figure well illustrates the general arrangement and functioning of the parts. 2 is one member of the body bolster, which is bolted to the body portion of the center bearing 6, which turns and also oscillates in any direction on the truck center bearing 5, this motion being permitted while the body is supported by the side bearings 23 and 23', the bearing surfaces of which, together with the surfaces of the bearings 5—6, lie in the same spheri-

cal figure. As indicated in Fig. 5, the bearings illustrated herein, which are designed for the larger type of city traction car, have a radius of ten feet. It will be observed in 5 all the figures that the actual surface of the bearings is only a small fraction of the total surface of the sphere, because the amplitude of motion of any of the parts is small. The 10 rotatory motion obviously requires a very much greater travel of the parts than the oscillatory or radial motion, but I do not 15 wish it to be understood that the specific determination which I have made of these two components is general in its application, 20 nor in any sense limiting as to scope. Any 25 dimensions may be adopted which are suitable for a particular case, the broad principle being that of universal motion of the car body combined with perfect support on the trucks in all positions. It may be noted in Fig. 1, that any angular displacement of the 30 wheels, either W or W' , being on a spherical curve, results in the wheels being moved outward so as to offer increased resistance 35 to thrust on the track curve.

Referring now particularly to Figs. 3 to 5, 1—2 represents the car bolster, and 3—4 the truck bolster, each formed of two metal members secured together by bolts and 40 braced against strain. The car bolster is properly shaped at its ends to receive the sills or other frame members of the car body, and is supported at three points, in 45 the middle by the center bearing 6, which rests upon balls 19 in a raceway carried by the truck center bearing 5, and at the two 50 ends by the side bearings 23—43 and 23'—43', in each of which are balls in curved raceways, all the raceways permitting 55 universal motion of the balls, within predetermined limits. Means are provided, and will presently be described, for preventing displacement of the balls during irregular motion of the car body or truck.

45 In Fig. 3 the bearings are all shown in plan, parts being dotted in under the bolster member 1. The center of horizontal rotation is in the axis of the truck center bearing 5 in all positions, and this when prolonged passes through the center of the sphere whose lower surface is indicated in Fig. 5. All motion in vertical planes is 50 around the center of this sphere. Theoretically, the car body will follow a constant path bearing a definite relation at all times 55 to the direction of the track and without lateral displacement. Practically, the body will be lifted and given some angular displacement in passing curves, but owing to 60 the freedom of movement of the trucks, this is accomplished without sudden strain or shock, and in all positions, the thrust on the bearings is direct, and is distributed among the various balls.

65 The detail construction of the center bear-

ing is as follows: The truck bearing 5 is secured to the bolster 3—4 by throughbolts 13, and is formed with a horizontal flange carrying the ball-ring 10, and a vertical hollow stud 8 with a rounded head. The 70 car bearing 6 is a drop member having a hollow body with curved interior face 9 surrounding the curved head of the center stud 8 with a slight clearance on the sides. The curvature of the bearing faces 8 and 9 75 is of some importance, as it is here that all lateral strains are taken up, without interfering with the vertical rotation of the truck. The body 6 has a horizontal flange carrying the ring 15 in which is formed the upper 80 raceway or bearing for the balls 19. Both rings 10 and 15 are shown in section in Fig. 5 and their opposed faces are curved in section as shown, the curvature of the upper ring 15 being approximately the same as the 85 curvature of the balls, while the curve of the lower raceway 10 is widened out to permit lateral travel on the surface of the sphere. The upper ring 15 is held in place by a retaining ring 16, with a chamfered edge 90 underlying the edge of the ball-race ring. This retaining ring is secured to the body flange by bolts 17. Since the position of the balls with respect to the car body should be constant for all positions of the truck, for obvious reasons, I provide a guard ring 20, secured to the body flange by bolts 22, this guard ring being slotted on both sides beneath the ball-race 15 to receive the balls. 100 The sides of the slots are beveled and their width is a little less than the diameter of the balls which are thus prevented from dropping out of position. The ring 10 constituting the lower ball-race is also held in position on the truck bearing flange by a 105 retaining ring 11, secured to the truck bearing flange by bolts 12. The upper bearing body 6 is secured to the car bolster by throughbolts 18; which with the side bearing bolts 44 preferably pass through horizontal members of the car body frame. The body 6 is centrally perforated to permit the passage of the kingbolt 7. The clearance around this bolt which is necessary to permit lateral motion is provided in the stud 8, 110 and is greater in the direction of the car length than transversely thereto, being sufficient however in all directions to permit the full motion for which the other parts are 115 designed.

120 Fig. 4 is a plan view of the truck bolster with the lower center and side bearings exposed. Fig. 6 is a detail view of the center bearing along the section line $x-x$ of Figs. 4 and 5. By comparing these two views it 125 will be observed that the head 8 is somewhat elongated in the direction of the car length, with rounded bearing surfaces as already described which however are normally in contact with the opposed bearing surfaces 130

9 in the body 6, fore and aft. The reason for this will be apparent upon a moment's reflection. The truck swings from side to side and may also turn to a limited extent 5 fore and aft, but there is not the same necessity for clearance in the latter motion that there is in the former, the curvature of the bearing surfaces at 8 and 9 being such that they will travel without binding, while constantly permitting the communication of 10 forward or backward thrust or tractive power from the truck to the car body, without loss. Thus the kingbolts serve merely to prevent displacement or disconnection of 15 the parts, especially in case of accident, such for example as the fracture of the head 8.

The detail construction of the side-bearings is as follows: These bearings are rights and lefts, as shown in Figs. 4 and 5, but each 20 pair is identical in every other respect. The side-bearing 23, shown on the right-hand side of Figs. 4 and 5, will be referred to particularly, and is illustrated on an enlarged scale, in Figs. 8 and 9. This bearing 25 has for its essential parts a pedestal 23, secured by bolts 24 to the end of the truck-bolster; a strut 43, secured by bolts 44 to the car-bolster; bearing-plates 25 and 45 carried on the pedestal and the strut respectively, and balls 34 traveling between plates 30 in the raceways.

The pedestal 23 (of the truck side-bearing) has an outside over-turned flange 30 and a parallel inside over-turned flange 31, 25 both of these following the arcs of circles having their center in the axis of the center bearing. Sliding under these flanges, is a linear ball-guard 32, having a slot cut radially in it, to receive the three balls 34, 40 as shown in section in Fig. 8. As the balls roll from end to end of the race-plate 25, this guard 32 is carried with them and slides back and forth under the flanges 30-31. So long as the upper plate 45 45 presses down on the balls steadily, just so long will the balls remain in proper position with respect to the two plates 25 and 45, if permitted to roll freely. Suppose, however, that in the middle of the travel, 50 the car-body is lifted slightly by a lurch or the like, so that pressure of the plate 45 is momentarily removed from the balls 34 while the rotary motion of the truck continues. The result would be that with extreme 55 relative displacement of the body and truck, the balls would have traveled only part way. Secondly, as the truck straightened up, with constant pressure on the balls they would be carried back to the reverse end of the ball race 25, and then, further travel being impossible, the continued motion of the plate 45 might either grind them flat or crack them, and in any event they would be left out of position to afford proper 60 support to the car-body. It is the function

of the linear ball-guard 32 to prevent such an occurrence. It should be further noted that if the balls were free, they might be similarly driven inward or outward along a radial line in their race-ways 25, and then, 70 if the car-body were lifted suddenly, might be left in displaced position when the car-body and truck resumed their normal positions. To prevent this occurrence is the function of what I call the radial ball guard 75 33, essentially a strip sliding radially under the bridges 35 and 36 on the guard-plate 32. This plate 33 has three openings, each large enough to receive one of the balls 34, so that these balls are kept in proper position 80 with regard to each other at all times. They can roll concurrently, carrying the plate 33 with them in a radial direction, and they can roll along their race-ways, carrying the plate 32 with them (as well as the plate 33 there- 85 on) in a similar direction.

Rising from each of the bridges 35 and 36 is a small lifting-bracket. The outer one of these brackets has a vertical member 41, and an overlying horizontal member 39, 90 while the inner bracket has a vertical member 42 and a horizontal member 40. By reference to Fig. 5, it will be seen that the arms 39 and 40 project over the curved flanges 46 and 47, forming the inner and 95 outer lower edges of the strut or body-bearing 43. Normally these parts are not in contact, there being a sufficient clearance between each flange 46 or 47 and each arm 39 or 40, to permit free travel of the body-bearing 43 and its plate 45. If the car-body lifts, however, so as to remove the plate 45 from contact with the balls 34, the arms 39 and 40 will be engaged by the flanges 46 and 47, and carried along with the bearing 43 on 100 the body. In order to make certain the engagement of the parts 39-46 and 40-47, I prefer to notch the upper surface of each flange 46-47 in a continuous series of serrations, as shown in Fig. 7. In such case 110 the members 39 and 40 are provided with knife edges to engage the serrations. By this means, displacement of the balls with respect to the body is rendered impossible, because if the car-body jumps, it merely lifts 115 the ball-cages or guards and carries them along with it. When it returns it will roll them back to their normal position, and if it should happen to jump back it will carry them with it again.

There are a number of mechanical details which I will mention, but which of course may be varied at will. Among these are the end gibbs 26 and 27, which hold the lower race-way in position, and similar gibbs 48 125 for the upper plate 45. The lower gibbs are held in place by bolts 28 and 29. Similar bolts secure the upper gibbs in place. The bridges 35 and 36 are secured by screws or rivets 37 and 38, best shown in Fig. 9 in 130

dotted lines. It should be noted that Fig. 5 is partly in perspective, since the outlines are along curves, so that straight line projection is precluded.

5 It is thought the operation of my invention will be sufficiently clear from the foregoing description and the accompanying drawings. To recapitulate, however, the trucks are free within certain limits to turn 10 upon the body in all directions, the fore and aft tractive contact between the head 8 and the bearing surface 9 in the center-bearing being at all times preserved. The center- and side-bearings are arranged to present 15 rolling parts, which are all in the surface of a great sphere shown in the drawings as having a radius of ten feet, and angular displacement in any vertical plane passing through the axis of the center-bearing is 20 possible to each truck, while the side-bearings provide sufficient lateral support in all positions, and transmit the thrust from the body to the truck, and so to the wheels. The center bearing balls 19 travel in a circle, 25 as shown in dotted lines in Fig. 3; and the side bearing balls 34 travel in arcs of circles. The race-ways for all of the balls are broadened along radial lines so as to provide for radial motion of all the balls, and in the side 30 bearings double cages or guards are provided normally traveling with the balls, but adapted to be engaged by the body parts and forced to travel with the body in any abnormal action which might otherwise result in relative displacement.

I am aware that many changes and modifications may be made in the apparatus thus described, without departing from the invention, and I wish it distinctly understood 40 that I contemplate all such non-essential changes as fall fairly within the scope of the appended claims.

Having thus described my invention, what I claim and desire to secure by Letters Patent of the United States is:

45 1. The combination of a vehicle body and a plurality of wheeled trucks therefor spaced apart longitudinally of the body, each truck comprising center and side bearings to permit universal movement, the several bearings of each truck being mounted on the surface of a sphere having its center vertically above the bearings.

50 2. The combination of a vehicle body and a plurality of wheeled trucks therefor spaced apart longitudinally of the body, each truck comprising center and side ball bearings to permit universal movement, the several bearings of each truck being mounted 55 on the surface of a sphere having its center in a vertical plane transversely of the body, and means for permitting a limited side play to the balls contained in said bearings.

3. The combination of a vehicle body and a plurality of wheeled trucks therefor, of center and side ball bearings therebetween, the bearing surfaces of each truck being mounted on the surface of a sphere the center of which lies above the truck in 70 a vertical transverse plane, the center bearing being connected by a king-pin and having a ball and socket joint to afford freedom in all planes, and means in the side bearings to permit lateral movement of the 75 balls in their casings in different planes.

4. The combination of a vehicle body and truck therefor, a central king-pin connected between the two, a ball and socket connection for the king-pin connection to absorb 80 thrust to permit universal relative motion and an anti-friction bearing for connection at the sides thereof and spaced apart therefrom, said lateral bearings being mounted in the surface of a sphere having its center 85 in a vertical plane transversely of the body to permit easy rocking of the entire car body and lateral shifting to accommodate track curves.

5. The combination of a vehicle body and a plurality of wheeled trucks therefor, said trucks being spaced apart longitudinally of the vehicle and each having center and side bearings, each of the latter bearings comprising an upper and a lower member 90 carrying opposite ball race plates, each race-way being curved on the arc of a circle coaxial with the center bearing, and also curved in the surface of a sphere including both side and center bearings, and having its 95 center in a prolongation of the axis of the center bearing.

6. The combination of an elongated vehicle body and two longitudinally spaced wheeled trucks adapted to support said body in travel over a railroad, each of said trucks having a limited range of angular movement about a central point as respects said body and supporting the same by contact therewith through a plurality of bearing surfaces, each and all of said bearing surfaces lying in the surface of a sphere the center of which lies in each case in a vertically extending line passing through the central point of angular movement aforesaid.

7. The combination of a vehicle body and wheeled truck therefor having a limited range of angular movement with respect thereto in the horizontal plane, of three 120 spaced transversely arranged bearings therebetween, one of which is centrally located and the other two of which lie one on each side of and spaced apart from the one, and means permanently centering the 125 said body and truck as respects the central bearing, the said three bearings all lying in the surface of a sphere the center of

which lies in a vertically extending line passing through the aforesaid centering means.

8. The combination of a vehicle body and 5 a wheeled truck therefor, a transverse body bolster between the body and the truck, a pivotal connection between the truck and the center of the bolster, limiting the relative longitudinal movement of body and 10 truck, but permitting free angular movement through a determinate range, a central thrust bearing adjacent said pivotal connection, the bearing surfaces of which lie in the surface of a sphere having its

center in a vertically extending line passing 15 through said bearing, and a side bearing on each side of and spaced apart from said central thrust bearing and between the said truck and bolster, the surfaces of said side bearings lying in the surface of the 20 above defined sphere together with the surfaces of the central thrust bearing aforesaid.

In testimony whereof I affix my signature in presence of two witnesses.

HENRY B. NICHOLS.
